UNITED STATES PATENT OFFICE.

PAUL A. CHAMBERLAIN, OF CHICAGO, ILLINOIS, ASSIGNOR TO MOHAWK CORPORATION OF ILLINOIS, OF CHICAGO, ILLINOIS, A CORPORATION OF ILLINOIS.

RADIOTUBE SOCKET.

Application filed October 23, 1926. Serial No. 143,535.

This invention relates to sockets for radio tubes, and more particularly to clips or terminals for use with such devices, and has for its principal object to provide an extremely simple construction of clip of the character described, capable of being readily applied to a panel or base and forming therewith a tube socket capable of supporting tubes with varying lengths of prongs or terminals, without requiring any adjustment thereof.

The invention may best be understood by reference to the accompanying drawing, in which

Figure 1 is a plan view of a top view of a base panel to which my improved form of clip is applied to form a tube socket, with parts broken away to show the position of one of the clips.

Figure 2 is an enlarged view in perspective, showing one of the clips,

Figure 3 is a sectional view taken on line 3—3 of Figure 1,

Figure 4 is an enlarged sectional view taken on line 4—4 of Figure 1,

Figure 5 is a sectional view taken on line 5—5 of Figure 1.

Referring now to details shown in the drawing, 10 indicates a subpanel or base, having a plurality of holes, 11, 11, (herein four) arranged and disposed to receive the four base terminals or prongs 12, 12 of the ordinary commercial form of radio tube or audion. In the drawing, Figure 1, these prongs are shown in section, the remaining parts of the tube being omitted, as unnecessary for an understanding of the present invention.

In association with each of said terminal holes 11, 11, I provide a metal clip 15. This clip is formed of a single relatively flat piece of metal, preferably sheet metal, formed by ordinary stamping and bending operations in the shape shown which consists in two upright wing portions 16, 16, joined together near one end by a portion 17, and spaced apart at the opposite end to form a pair of spring contacts 18, 18, arranged in registering position beneath its terminal hole 11, as clearly seen in the drawings. These spring contacts engage opposite sides of the tube terminals 12, when the tube is inserted in place, and hold said tube firmly by spring tension.

Means for securing the clip in place comprises a pair of laterally extending sup-

porting parts 19, 19, adjacent the rear end of the clip and adapted to engage the under surface of the base 10, a pair of upwardly extending projections 20, 20, which are normally continued upwardly in the same plane as the main wing portions 16, 16, at a point intermediate their ends, and another, shorter, pair of projections 21, 21, adjacent the extreme rear end of the clip, all as shown in Figure 2.

In applying the clip to the base panel 10, the latter is provided with a pair of apertures 22 and 23, in alignment with each terminal hole 11, (see Figure 1). The larger pair of projections 20, 20 are passed upwardly through the inner hole 22, and the upper ends are then turned or bent outwardly so as to clamp the clip with parts 19, 19, and upper edges 18, 18, of wings 18, 18, held against the lower surface of the panel, but permitting freedom of lateral bending of the outer ends of terminal contacts 18, 18. The shorter projections 21, 21, fit in the rearmost hole 23, so as to restrain the clip from twisting movement.

Electrical connections may be made with each clip by soldering to a terminal piece 26, formed at the bottom and rear end thereof, as shown, or else, by riveted connection with the laterally projecting supporting parts 19, 19, the latter being shown with holes 19^a, 19^a for this purpose, if desired.

The use of the device above described will now be manifest to those skilled in the art. The clip is capable of being manufactured most economically and in large quantities, and of being applied to base panels with a minimum amount of labor or expense. The resulting device forms a superior holder for standard radio tubes, without requiring any changes for tubes having terminals of different lengths.

I claim as my invention:

1. In a tube socket, a base provided with apertures for receiving the terminals of a tube, and a plurality of terminal clips for engaging said terminals supported on the under side of said base, and each comprising a piece of flat sheet metal bent with two side portions disposed in planes substantially perpendicular to said base, parts of said side portions disposed beneath one of said terminal apertures and being adapted to contact with the tube terminal under tension, and other parts projecting upwardly

2
through said base and with their upper ends bent laterally to secure said clip to said base.

2. In a tube socket, a base provided with apertures for receiving the terminals of a tube, and a plurality of terminal clips for engaging said terminals supported on the under side of said base, and each comprising a piece of flat sheet metal bent with two side portions disposed in planes substantially perpendicular to said base, parts of said side portions at one end of said clip disposed beneath one of said terminal apertures, and being adapted to contact with the opposite sides of tube terminals under tension, and 10 other parts projecting upwardly through said base and with their upper ends bent laterally to secure said clip to said base.

3. In a tube socket, a base provided with apertures for receiving the terminals of a tube, and a plurality of terminal clips for engaging said terminals supported on the under side of said base, and each comprising a piece of flat sheet metal bent with two side portions disposed in planes substantially

perpendicular to said base, parts of said side portions at one end of said clip disposed beneath one of said terminal apertures and being adapted to contact with the opposite sides of tube terminals under tension, other parts projecting upwardly through said base and with their upper end bent laterally to secure said clip to said base, and other projections extending upwardly into interlocking engagement with said base to hold said clip from twisting relative thereto. 25 30 35

4. A terminal clip for tube sockets comprising a single piece of flat sheet metal bent substantially in U-shape, with freely projecting end portions spaced laterally from each other to hold a terminal under tension 40 therebetween, and upwardly projecting securing portions adapted to be extended through apertures in a base member with their upper ends bent laterally to hold said clip in place thereon. 45

Signed at Chicago, Ill., this 20 day of Oct., 1926.

PAUL A. CHAMBERLAIN.
